UNITED STATES PATENT OFFICE.

ERNEST H. PEABODY, OF PELHAM MANOR, NEW YORK.

AIR REGISTER FOR FUEL BURNERS.

Application filed April 19, 1923. Serial No. 633,169.

To all whom it may concern:

Be it known that I, ERNEST H. PEABODY, a citizen of the United States, and resident of Pelham Manor, county of Westchester, 5 State of New York, have invented certain new and useful Improvements in Air Registers for Fuel Burners; and I do hereby declare the following to be a full, clear, and exact description of the invention, such as 10 will enable others skilled in the art to which it appertains to make and use the same.

This invention relates to a system or air control registers for fuel burners, preferably of the mechanical atomizing type which 15 finely atomizes the fuel entirely by pressure and produces a hollow conical spray, and has for its objects to produce a register that will deliver the required air supply uniformly and in a direction converging to the 20 flame so that each particle of fuel will be supplied with its required amount of oxygen for complete combustion within the cone of fuel as well as on the outside surface.

It is well known that efficient combustion 25 can be produced only by atomization of the oil into its finest particles. If each particle is far enough apart from its neighbor to permit being completely surrounded with the proper amount of oxygen, complete and 30 perfect combustion will result.

The foregoing and other features of my 35 invention will now be described in connection with the accompanying drawings, forming part of this specification, in which I have represented my air register in its preferred form, after which I shall point out more particularly in the claims those features which I believe to be new and of my own invention.

40 In the drawings Figure 1 is a central vertical sectional view of my register mounted in a furnace front.

Figure 2 is a view, partly broken away, of the front plate.

45 Figure 3 is a view of my register partly broken away with the front plate removed.

In the carrying out of my invention, the 50 refractory wall 1 of any suitable furnace is provided with a circular opening 2 into which a conical annular ring 3 is secured by any convenient means such as bolts 4 to the front plate 5. The inner end of the conical ring 3 is flanged as at 6 forming a right angle with the refractory wall 1 of the furnace, which is filled in with plastic refractory material 7.

Coaxial with the conical member 3 I provide a cylindrical member 8 having a reduced portion or sleeve 9 adapted to hold the burner 10 provided with tip 11, fuel supply 12 and diffuser plate 13. The burner is adapted to slide within the sleeve and be held in adjusted position by means of the thumb screw 14. Spirally arranged deflector plates 16 hold the conical member 3 and the cylindrical member 8 in spaced relation and the latter is provided with openings 15 which are located between the deflector plates 16 and form a plurality of air ducts which converge from the outer to 70 inner portion having a section of maximum restriction near the combustion chamber substantially like the converging nozzle used in elastic fluid turbines of the impulse type for converting pressure into velocity. 75

Mounted on the sleeve 9 I provide a front plate 20 adapted to slide and rotate to control the air passing into and through the air passages in the register.

I provide a plurality of openings 21 in 80 the flat face 19 of the cylindrical portion 8 and in front of these openings I provide a shutter 26 operated by handle 22 suitably guided as at 23 and secured in its adjusted position by thumb screw 24. This shutter 85 26 is provided with openings 27 similarly arranged with holes 21 in plate 19.

From the foregoing description it will be apparent that the air passages between the 90 conical member 3 and the cylindrical member 8 separated from each other by the spiral partitions 16 converge toward the combustion chamber. Each passage gradually changes in section to maximum restriction at the combustion chamber end. 95

The air of combustion in flowing through a passage so proportioned will expand adiabatically to the lesser pressure existing at the throat and issue uniformly as a continuous stream possessed of a definite velocity in a direction convergent to the flame so that it will penetrate the conical layer of ignited fuel flowing from the burner and enter the furnace as a highly incandescent gaseous mixture. 105

I claim:

1. An air control register comprising an atomizer adapted to deliver fuel in the shape of a conical spray into a combustion chamber, a frusto-conical ring-like member adapted to fit into an opening in the front of the combustion chamber, a cylindrical mem-

ber coaxial with the frusto-conical member, a plurality of spirally arranged deflector plates interposed between and connecting the conical member and the cylindrical member

6 and adapted to direct the air into the combustion chamber, and rotatable and slid-
able means for the control of the air through the passages between the two members.

2. An air control register comprising an 10 atomizer adapted to deliver fuel in the shape

of a conical spray into a combustion chamber, a frusto-conical member adapted to fit into an opening in the combustion chamber, a cylindrical member in spaced relation

15 thereto and spaced from the atomizer and a plurality of spirally arranged deflector plates interposed between and connecting the frusto-conical and cylindrical members adapted to direct the air to the combustion chamber so that it impinges upon the cone of fuel.

3. A device as recited in claim 2 with the addition of means for controlling the amount of air entering between the frusto-conical 20 and cylindrical members.

4. An air control register comprising a frusto-conical member adapted to fit into an opening in the furnace front, a member provided with a cylindrical body portion

30 and a reduced cylindrical sleeve adapted to receive an atomizer, a plurality of spirally arranged deflector plates interposed between the frusto-conical member and the cylindrical body portion, and rotatable and slid-
able means for control of the passage of air through the openings between the deflector plates.

5. An air control register comprising an outer frusto-conical ring-like member adapt-
40 ed to be secured to a furnace front, an inner cylindrical portion for the admission of air, and a series of spirally arranged partitions securing the inner portion to the outer member in spaced relation.

45 6. An air register comprising an outer frusto-conical ring-like member adapted to be secured to a furnace front, an inner cy-
lindrical member provided with a reduced portion, a series of spirally arranged parti-
tions securing the inner member to the outer member, and a rotatable and slid-
able member mounted on the reduced portion of the cylindrical member for controlling the admission of air.

55 7. An air control register comprising an atomizer adapted to deliver fuel in the shape of a conical spray into a combustion chamber, a frusto-conical ring-like member adapt-
ed to fit into an opening in the front of

the combustion chamber, a cylindrical mem- 60 ber coaxial with the frusto-conical member and spaced from the atomizer, a plurality of spirally arranged deflector plates inter-
posed between and connecting the frusto-
conical member and the cylindrical member 65 and adapted to direct the air into the com-
bustion chamber, and means for the control of the air through the passages between said members.

8. An air control register comprising a 70 frusto-conical member adapted to fit into an opening in the furnace front, a mem-
ber provided with a cylindrical body por-
tion and a reduced cylindrical sleeve adapt-
ed to receive an atomizer, a plurality of 75 spirally arranged deflector plates interposed between the frusto-conical member and the cylindrical body portion, and means for con-
trol of the passage of air through the open-
ings between the deflector plates. 80

9. An air register comprising an outer frusto-conical ring-like member adapted to be secured to a furnace front, an inner cylindrical member provided with a reduced portion, a series of spirally arranged par- 85 titions securing the inner member to the outer member, and a member mounted on the reduced portion of the cylindrical member for controlling the admission of air.

10. An air control register comprising an 90 outer frusto-conical ring-like member adapt-
ed to be secured to a furnace front, an inner cylindrical portion having its outer face closed except for air openings, fuel supply means within said cylindrical portion, spi- 95 rally arranged partitions connecting the member and the inner portion, and means for controlling the passage of air through said openings.

11. A device as recited in claim 10 with 100 the addition of means for controlling the passage of air between the member and the inner portion.

12. An air control register comprising an outer frusto-conical ring-like member adapt-
ed to be secured to a furnace front, an inner cylindrical member having a closed outer end provided with openings and a reduced cylindrical sleeve to receive an atomizer, means for connecting the two members, 105 means for controlling the passage of air through said openings, and means slid-
able on the sleeve for controlling the passage of air between the two members.

In testimony whereof I affix my signa- 115 ture.

ERNEST H. PEABODY,
